3 Claims. (Cl. 141—12)

This invention relates to the filling and packing of material in containers and more particularly to process and apparatus for filling and packing granular and semigelatinous explosive materials into containers.

In the packaging art today it is highly desirable to pack containers with a desired amount of material at a uniform density. While this is important in the packaging and sale of most commodities, it is of particular importance in the explosives art, since the results obtained in blasting operations are often directly dependent upon the uniform packing of the explosive composition in its containers. In modern day blasting techniques where the trend is more and more in the direction of the relatively insensitive blasting agent, the furnishing of a blasting composition at a uniform density is of increasing importance to obtaining positive and uniform detonations with the conventionally employed detonating means such as blasting caps and detonating fuses.

For many years the standard dynamite package has probably been the 1 1/4 in. x 8 in. "stick." In developing the Hall type of machine the art has produced a packer which is satisfactory for this type and size of cartridge, and this general type of machine is generally used in the manufacture of small cartridges. The Hall type packer functions by the tamping of the explosive composition into the cartridge by means of tamping rods. In more recent years, however, cartridges of increased diameter and length have found use and at the present time cartridges in the order of 8 inches in diameter and 24 inches in length are commonplace. Packaging problems were experienced with these larger cartridges also, since it has been the general practice of the art to pack such cartridges by hand. However, these cartridges may be expeditiously packed at the present time by vibration in accordance with the disclosure of copending application Serial No. 134,530, filed December 22, 1949, now abandoned.

For many years there has been a desire on the part of those engaged in blasting operations to employ small diameter cartridges of increased length such as cartridges 1 1/4 to 2 inches in diameter and from 12 to 24 inches in length. These cartridges have been available in very limited quantity, however, in view of the fact that it has not been found possible to satisfactorily modify the Hall type packer to produce such cartridges due at least partially to practical mechanical limitations of this type machine. Since such cartridges can be satisfactorily consolidated by vibration if the material can be uniformly introduced into the cartridge in a proper manner, it has been desired to produce this type of cartridge with a vibratory packer. This effort, however, has not been successful due to the fact that no satisfactory means has been developed for uniformly feeding the explosive into the small diameter cartridge during vibration. Clearly, it is unfeasible from the commercial standpoint to introduce the material by hand. Vibratory feeders have proved unsatisfactory in that the feeding of the ex-

2

plosive into the small diameter cartridges has not been rapid enough or satisfactorily uniform and in any practical machine where a number of cartridges must be packed at once, nonuniform densities are obtained due to the fact that some of the cartridges became filled a substantial period before the others and then were subjected to vibration in the filled condition for an undesirably long period. At the present time, therefore, there is no equipment disclosed in the art which has been found satisfactory for packing long cartridges of reduced diameter. The few that have been available in the past either have been packed by hand or else have been produced by loading shorter cartridges packed on a Hall machine into a longer cartridge. Neither of these methods is commercially feasible.

Now in accordance with the present invention, there has been developed a process and equipment to carry out such a process by means of which cartridges of any reasonable size and length can be quickly produced in large numbers with uniform packing density.

Generally described, the present invention comprises a process for filling and packing materials into containers which comprises forcing the material through a passageway and into a container by means of a reciprocating member, subjecting the container to vibration to consolidate the material in the container, shortening the effective stroke of the reciprocating member when the container is filled to the desired density, continuing reciprocation of the member with a shortened effective stroke until the passageway is at least partially filled with a packed core of the material, replacing the filled container with an empty container, and lengthening the effective stroke of the reciprocating member to force the packed core into the empty container. Also included in the invention is equipment for carrying out such a process, a preferred embodiment of which comprises a platen, means for vibrating the platen, a hopper disposed above the platen containing at least one nipple to engage the mouth of a container to be filled, means for delivering the material to be packed to the hopper, and a reciprocable rod aligned with each nipple, the stroke of each rod being such that when fully extended the end of the rod does not extend substantially beyond the mouth of the nipple, said rod forcing the material in the hopper through the nipple and said vibrator consolidating the material in said container. In employing the process and the apparatus in this preferred embodiment of the invention, therefore, the material to be packed is uniformly forced through the nipples of the hopper from where it falls freely into the vibrating container.

In a further preferred embodiment of the apparatus of the invention the reciprocating members or rods will be attached to a column crosshead assembly disposed above a hopper with each rod in coaxial alignment with a nipple in the hopper assembly. The stroke of the rods will be such that at their lower limit of travel they do not extend substantially beyond the mouth of the nipples. Preferably, the individual rods will be yieldably mounted in the crosshead assembly so that when the containers have been filled, the effective stroke of the rods will be shortened and a suitable core will be packed in the nipple. Then when the cartridges which have been consolidated by vibration are removed, the nipples will be sealed and prevent loss of powder therethrough until an empty set of cartridges replaces the filled set. At this point the effective length of the stroke can be automatically lengthened in a suitable fashion and the initial stroke after the lengthening will force the core from the nipple into the container and thereafter the material will be continuously introduced into the fresh

containers as before. While this effective shortening of the stroke of the rods can be effected in a number of suitable ways, it is preferred in accordance with a further embodiment of the invention to employ a feeding or tamping assembly which comprises a cylinder, a reciprocable rod passing longitudinally through the cylinder, sealing means disposed between rod and cylinder adjacent each end of the cylinder, a piston mounted on the rod within the cylinder and disposed in sealed, slideable relationship with the cylinder walls, a first port for introducing pressurized fluid to one end of the cylinder to exert pressure on one end of the piston, a second port for introducing pressurized fluid into the cylinder on the opposite side of the piston, fluid flow through the second port being prevented when the piston is disposed adjacent the second port, said rod being movable in the direction of the first port for a distance sufficient to move the piston past the second port when a force sufficient to overcome the pressure of the fluid entering the first port is longitudinally applied to the rod, said rod being further movable in the same direction for a distance sufficient to prevent further contact with the work when the fluid entering the second port exerts a pressure on the other surface of the piston sufficient to overcome the pressure exerted by the fluid entering the first port, and said rod being movable in the opposite direction for a distance sufficient to engage the work when the pressure exerted by the fluid from the second port is released or overcome.

The effective stroke of the reciprocating members or rods can also be shortened by employing a friction joint between the rods and a crosshead support member. In like manner, a suitably weighted rod may be employed which is freely mounted in a crosshead support. A further alternative for shortening the effective stroke of the rods is to automatically lower the platen and hopper when all containers are filled, allow packing of the cores in the nipples, and then further lower the platen for discharging the shells.

Any desired number of nipples and reciprocating rods may be employed as desired. In accordance with a further embodiment of the invention a plurality of shuttles for the cartridges may be rotatably mounted and suitably coordinated so that fresh shells may be inserted into one shuttle and filled shells may be crimped in a third shuttle during the course of the loading of material into the shells disposed in the second shuttle.

It is generally preferred that the stroke of the reciprocating rod be so limited that the rod only forces the material completely through the nipple and does not tamp pack the material in the container per se. However, it will be appreciated that in the crosshead assembly specifically illustrated in Figs. 1, 2, and 3 the stroke can be of any length desired, depending on the length of the cylinders, without changing the operating principle. Thus, if desired, the stroke can be lengthened to the point desired and this particular crosshead assembly may be employed to tamp pack as well as feed.

Having generally described the invention, more particular illustration will be given with reference to the drawing in which Fig. 1 is a part elevational, part sectional front view of a packing machine in accordance with the invention; Fig. 2 is a part elevational, part sectional end view taken along line 2-2 of Fig. 1; Fig. 3 is a sectional detail view of the yieldable mounting means for the reciprocating rods in the machine shown in Fig. 1; Fig. 4 is an elevational diagrammatic view of the crimping means employed in the machine shown in Figs. 1 and 2; Fig. 5 is a schematic diagram showing an embodiment in which a plurality of rotatably mounted shuttles is employed; and Fig. 6 is a part elevational, part sectional view of a preferred pneumatic vibrator for use in the packing apparatus of the invention.

Referring to Figs. 1 through 4, the packing machine shown is supported by a frame 10. A platen 11 is sup-

ported adjacent each end on resilient mountings 12 and may be raised or lowered by means of fluid cylinders 13. A pneumatic vibrator 14 is bolted to the under side of the platen 11 with the power stroke of the piston 15 being in the vertical direction or normal to the plane of the platen 11. A rack 16 for receiving filled cartridges is rotatably mounted on an axle 17 and is actuated by pneumatic cylinders 18. A crimping assembly 19 is supported on rods 20 in a position directly above the rack 16 when it is in the vertical position shown in Fig. 2. The crimping assembly is split as shown in Fig. 1 into two sections 21 and 22. The lower section 22 contains the folding dies 23, while the crimping plungers 24 are mounted in the section 21 and extend downwardly into dies 23. Air cylinders 25 are mounted on section 21 and contain pistons 26. Piston rods 27 lead from the piston 26 through the member 21 and are anchored in the member 22. The crimping assembly is actuated by cylinders 28 mounted at each end of the machine. The piston rods of the air cylinders 28 are connected to levers 29 which are in turn connected to the pull rods 20 which pull the mechanism downward to make the crimp.

A shuttle 30 is pivotally mounted at each end on arms 31 which are in turn pivotally mounted on the frame. A clevis 32 extends from the base of the shuttle 30 and a clevis 32a extends from the base of the arm 31. Fluid cylinders 33 and 34 are provided to actuate the movement of the shuttle during operations, the piston rod of cylinder 33 being connected to clevis 32 and the piston rod of cylinder 34 being connected to clevis 32a. When the shuttle 30 is in the position shown in Fig. 2, the actuation of the fluid cylinder 33 causes the bottom of the shuttle to swing outwardly to the position shown by the dotted lines at 35. When cylinder 34 is actuated and the arms 31 are pulled downward, the shuttle 30 then takes the horizontal position shown by the dotted lines at 36. In Fig. 1, cartridges 37 are shown with their bottoms resting on the platen 11. Directly above the shuttle is mounted a hopper 38, the bottom of which is formed by a nipple plate 39. The nipples 40 enter into the mouths of the cartridges 37 when the shuttle and platen are raised to filling position. Tandem stirrers 41 are mounted in the hopper 38 on either side of the nipples 40. A crosshead assembly 42 is disposed above the hopper 38 and is reciprocated in its entirety by cranks 43 on a shaft leading to the power source. Supported in the crosshead assembly 42 are a plurality of reciprocable metal rods 44. Wooden tamp sticks 45 are joined to the metal rods 44 and terminate in rubber tips 46. Disposed about the rod 44 between horizontal members 47 are airtight cylinders 48. Secured to the rod 44 within the cylinder 48 is the piston 49. Low pressure air is introduced to the cylinder 48 through port 50 by means of pipe 51 and header 52. High pressure air is introduced to the cylinder 48 through port 53 by means of pipe 54 and header 55. As shown in Fig. 3, the piston 49 is disposed in the cylinder 48 adjacent the port 53 and is preventing the introduction of the high pressure air.

Above the upper crosshead member 47, each rod passes through an upper cylinder head supporting an orificed cam member 56 and is prevented from disengagement by a nut 57. Each cam is freely movable by the rod. At the lower limit of travel of rod 44, when its effective stroke is at the longest value, the nut 57 engages the cam 56. As the rod approaches its upper limit of travel and its effective stroke is at the shortest value, the upper end of the rod engages the projection 58 and carries the entire cam upward until the piston 49 reaches the limit of its upward travel in the cylinder 48. When the rod 44 is up, the portion 59 of the cam 56 clears the elongated lever 60 which is attached to a rotatable, spring loaded rod 61. This rod 61 is unable to rotate clockwise until all cams 56 of all rods 44 have cleared the lever 60. When the entire lever 60 is cleared, the rod 61 rotates in a clockwise direction to actuate valving

mechanisms (not shown), the functioning of which will be hereinafter described. When the rods 44 are returned to the down position, the first cam or cams to contact the lever 60 forces it to rotate counterclockwise to become cocked or loaded for the next cycle. The material to be packed is delivered to the hopper 38 by any suitable means such as a moving belt conveyor or the like.

The machine of Figs. 1 through 4 operates as follows. The explosive composition to be packed is introduced uniformly to the hopper 38 by suitable means (not shown) such as a moving belt conveyor. The shuttle 30 is initially loaded with empty shells. The shells are loosely held in the shuttle and are free to move longitudinally therein. As shown in Figs. 1 and 2, the shuttle is in the upright position and the platen 11 is raised by means of cylinders 13 until the shells 37 engage the nipples 40. The stirrers 41 are continuously rotated and the crosshead assembly 42 is made to continuously reciprocate synchronously with the stirrers 41 by means of cranks 43 which are connected to a power source (not shown). As soon as the platen 11 is raised and the shells 37 engage the nipples 40, the vibrator 14 is automatically actuated. The sticks 45, continuously reciprocating with the crosshead, force the explosive through the nipples 40 and into the containers where it is continuously consolidated by the vibration imparted to the cartridges 37 by the platen 11. Due to uniform introduction of the composition into the hopper 38, the synchronous distribution by stirrers 41, and the action of the rods 45, the shells are filled practically simultaneously, thus exposing the explosive in each shell to practically the same amount of vibration. When the level of consolidated powder rises above the egress orifice of the nipples 40, the powder is then consolidated in the nipples 40 by tamping action of the sticks 45. All this time low pressure air is being introduced into the upper part of the cylinders 48 through the port 50. The pressure of this air is such that with each succeeding increment of powder that is packed in the nipples 40, the effective stroke of the rod 44 is shortened by compression of air in the upper part of the cylinder 48 by the piston 49. On the up-stroke of the crosshead assembly, however, the low pressure air again fully lengthens the stroke of the stick 45 and the next increment of powder packed in the nipple by the succeeding stroke is packed to a density sufficient to still further shorten the effective stroke of the stick 45. When each nipple is filled to the desired level, the piston 49 is raised by action of the powder packed in the nipple to a point where it passes port 53 and allows high pressure air to flow into the lower part of cylinder 48. The high pressure air then overcomes the low pressure air and the piston 49 is then forced into the upper portion of the cylinder 48 to withdraw the stick 45 from contact with the powder in the nipple or hopper. As the high pressure air forces each rod 44 to its upper limit of travel, each cam 56 is lifted and successively clears the lever 60. When the last rod 44 rises and the last cam 56 clears the lever 60, the spring loaded rod 61 is allowed to rotate clockwise to actuate a valving mechanism which shuts off the flow of air to the vibrator 14 and reverses the air in cylinders 13 to lower the platen 11. Lowering of the platen 11 allows the shells 37 to fall away from the nipples 40, whereupon the consolidated, continuous column of powder in the shell breaks away from the nipples which remain sealed by the cores packed therein.

Cylinder 33 is now actuated to swing the bottom of the shuttle 30 and shells 37 outwardly to clear the platen as shown by the dotted lines at 35. The loaded shells, loosely held by the shuttle 30, fall through the shuttle 30 into the rack 16. Cylinder 34 then is automatically actuated to swing down the now empty shuttle 30 to the horizontal position shown by the dotted lines at 36 in Fig. 2. A new group of empty shells is then inserted automatically into the shuttle 30 by an automatic shell feeding device (not shown). The cylinder 34 is then

actuated to swing the shuttle 30 back into the vertical position under the nipples 40. The platen 11 is then raised to engage the new shells with the nipples 40. At this point the high pressure air entering port 53 is drained off and the pressure below the piston 49 is released. The low pressure air then forces the pistons 49 down to extend the rods 44 to their full length below the crosshead. As the rods 44 are forced to their longest effective length, the nuts 57 force the cams 56 downward and the lever 60 is again depressed. The rod 61 is rotated counterclockwise, the valving mechanism is reversed and, with rod 58, is cocked or loaded for the next cycle.

The crosshead assembly 42 has continuously reciprocated during this time and with the first stroke of the extended rods 44 and sticks 45, the cores which were built up in the nipples 40 are pushed into the empty shells and the loading and packing operation is repeated. During the loading of this group of shells, the rack 16 which contains the loaded first group of shells is swung from the position shown in Fig. 2 to the vertical position shown by dotted lines 20 in Fig. 2 by means of air cylinder 18. Cylinder 28 is actuated, and the crimping mechanism 19 is pulled downward by rod 20. As the folding dies 23 turn the edges of the mouths of the shells inwardly, the member 21 which is maintained apart from the member 22 by cylinders 25, as shown in Fig. 1, forces the crimping plungers 24 downward through the folding dies 23 to complete the crimping operation. The pressure is then reversed in the cylinder 28 and the crimping assembly 19 is raised to its inactive position. The rack 16 is then forced outwardly by cylinders 18 to the discharging position shown by the dotted lines at 58 in Fig. 2. The finished cartridges are discharged to a waiting tray or moving belt as may be desired.

Except for supplying the material to be packed to the hopper or to a feeding belt and for supplying empty containers to the hopper of the shell feeding machine, the entire operation of the machine shown in Figs. 1-4 is automatic. The particular valving mechanisms employed for this particular machine are operated by air pressure and are fabricated from conventional components known to the art. Hydraulic or electrical mechanisms can be substituted if desired. The various cylinders of the embodiment specifically described were air cylinders. 45 Hydraulic cylinders of equivalent mechanical elements which will effect the necessary movement of the various parts of the apparatus may be substituted, if desired, without departing from the invention as set forth in the appended claims.

50 In the specific embodiment of the invention illustrated in Figs. 1-4, the crosshead has been made to reciprocate constantly, even though no material is being loaded during part of the cycle. The cycle can be so controlled that reciprocation of the crosshead takes place only during 55 actual filling operations. Furthermore, reciprocation of the crosshead can be effected by means of fluid cylinders instead of the gears and power source employed in the embodiment specifically described.

A further embodiment of the invention is shown in 60 Fig. 5 where three shuttles 62, 63, and 64, each containing a row of holes to receive shells, are shown pivotally mounted on a rotatable support 65. In order to increase the output of loaded cartridges, the assembly shown in Fig. 5 can be adapted to function with the hopper and 65 crosshead assembly of the particular embodiment shown in Figs. 1 through 4. In this modified structure the empty shells would be fed into the shuttles at station A by a shell feeder diagrammatically shown by dotted lines at 66. This shuttle would then be rotated to station B where loading and packing would take place as in the operation previously described. Crimping by means shown at dotted lines 67 and discharging of the filled shells would take place at station C as shown. Such a modification of the apparatus of the invention can also be tool to 70 automatic operation by suitable control means without

in any way departing from the generic scope of the invention. In addition, it will be desirable to modify the shuttles in this embodiment so that they can exert pressure on the shells to hold them in the shuttle while they are not resting on the platen. Such pressure can readily be obtained by employing split shuttles, the sections of which may be drawn together by suitable mechanical means.

As disclosed in copending application Serial No. 134,530, it has been discovered that the packing of materials into containers at high uniform density is best effected by means of vibratory movement in which the power stroke in each oscillation is applied in only one direction. Thus, in the embodiment of the invention shown in Fig. 1, it is preferred to employ a vibrator in which the power stroke of the piston is in the upward direction and the piston is allowed to fall free after each power stroke, cushioned only by the air escaping during the exhaust stroke. For many materials, particularly the lighter materials, the frequency of vibration is quite important to obtaining optimum results. Thus, it is often desirable to employ different vibratory frequencies when packing different types of materials. To obviate the necessity of changing vibrators, it is often desirable to use a vibrator with a controllable frequency such as that disclosed in U. S. 2,609,791. Although electric and hydraulic vibrators may be employed, if desired, best results are obtainable with pneumatic vibrators. From the standpoint of safety it is not desirable to employ an electric vibrator for the packing of explosives. Pneumatic vibrators are generally preferred over hydraulic vibrators due to the fact that the pneumatic vibrator is generally characterized by a higher frequency which is usually necessary to satisfactorily pack most materials from both the standpoint of ultimate density and the time required to reach that density.

In Fig. 6 is shown a part sectional, part elevational view of a pneumatic vibrator having a unidirectional power stroke which may be easily converted for use as a platen vibrator in accordance with the invention. A reciprocable piston 70 is disposed in a cylinder 71 formed by a casing 72. The lower portion of the casing 72 is formed by a cylinder head 73 which is held in airtight relationship to the remainder of the casing 72 by a gasket 74 and studs 75. An annulus 76 is formed in the wall of the cylinder at a point equidistant from the ends thereof. Passages 77 and 78 are formed in the outer periphery of piston 70 at points which register with the center of annulus 76 when the piston 70 is alternately at the end of either its exhaust or power stroke. A duct 79 leads from the passage 77 through the piston 70 to the bottom of piston 70. A duct 80 leads from the passage 78 through the piston 70 to the top of the piston 70. Duct 80 is plugged with a threaded plug 81. Exhaust ports 82 and 83 are disposed in the wall of the cylinder at a point equidistant from the ends of the cylinder. The distance between the exhaust ports 82 and 83 is such that during reciprocation one end of the piston begins to cover one exhaust port just as the opposite end of the piston begins to uncover the other exhaust port. A threaded air inlet port 84 is disposed in one side of the casing 72 and leads into the annulus 76. A threaded air inlet port 85 is disposed in the opposite side of the casing 72 and also leads into the annulus 76. A threaded plug 86 is disposed in the air inlet port 85.

The vibrator shown in Fig. 6 operates as follows. Pressurized air is introduced through air inlet 84 and flows into annulus 76 into the passage 77 and through duct 79 to the bottom of the cylinder 71. The piston 70 is forced upwardly by the pressurized air until the passage 77 travels beyond the annulus 76 and the exhaust port 82 is uncovered by the bottom of the piston 70. The upward stroke of the piston 70 is cushioned somewhat by the air cushion formed in the upper part of the

cylinder 71 once the upper portion of the piston 70 has closed off the exhaust port 83. At the completion of its upward power stroke the piston 70 falls freely with its downward fall being cushioned by the air cushion formed when the lower portion of the piston closes the exhaust port 82. As soon as the passage 77 again registers with the annulus 76, air is again admitted to the bottom of the cylinder 71. The duct 80 and passage 78 leading to the top of the piston 70 from the annulus 76 are provided to allow use of the vibrator shown with a power stroke in the opposite direction when the duct 79 is plugged and the duct 80 is unplugged. If both ducts are left unplugged, a conventional two-way power stroke is obtained. The passages 86, 87, and 88 which are plugged by studs 85, 89, and 90, respectively, are provided for attachment of a frequency control valve such as that shown in U. S. 2,609,791.

While it is generally desirable to employ a pneumatic, hydraulic, or electric vibrator to impart the necessary vibratory movement to the platen, the desired movement may be generated by other mechanical means.

It will be seen, therefore, that in accordance with the process and apparatus of the present invention it is now possible to produce uniformly loaded containers which are characterized by considerable length and a relatively small diameter. For example, in packing explosives, excellent results have been obtained with both free-flowing granular powders and semigelatinous compositions in cartridges from 1 1/4 to 2 inches in diameter and from 12 to 24 inches in length. However, the invention is clearly not limited in application to the packing of such containers, since it is apparent that it exhibits equal utility in the packing of any type of container. While the invention has been particularly described with respect to its application and utility in the explosives field, it is to be understood that the apparatus and process are equally applicable to other materials.

Since various modifications of the invention will occur to those skilled in the art which do not depart from the generic nature of the invention, it is intended that the invention be limited only by the scope of the appended claims.

This application is a division of copending application Serial No. 346,206, filed April 1, 1953.

45 What we claim and desire to protect by Letters Patent is:

1. A process for filling and packing material into containers which comprises forcing the material through a passage and into a container by means of a reciprocating member, subjecting the container to vibration to consolidate the material in the container, shortening the effective stroke of the reciprocating member when the container is filled to the desired density, continuing reciprocation of the member with a shortened effective stroke 50 until the passage is at least partially filled with a packed core of the material, replacing the filled container with an empty container, and lengthening the effective stroke of the reciprocating member to force the packed core into the empty container.

2. A process for filling and packing material into containers which comprises forcing the material through a passage and into a container by means of a reciprocating member, subjecting the container to vibration applied in the vertical plane, shortening the effective stroke of the reciprocating member when the container is filled to the desired density, continuing reciprocation of the member with a shortened effective stroke until the passage is at least partially filled with a packed core of the material, replacing the filled container with an empty container, 65 and lengthening the effective stroke of the reciprocating member to force the packed core into the empty container.

3. A process for filling and packing material into containers which comprises forcing the material through a 70 passage and into a container by means of a reciprocating

member, subjecting the container to vibration in the vertical plane, the vibration being such that in each cycle of oscillation force is applied to the container in only the upward direction, shortening the effective stroke of the reciprocating member when the container is filled to the desired density, continuing reciprocation of the member with a shortened effective stroke until the passage is at least partially filled with a packed core of the material, replacing the filled container with an empty container, and lengthening the effective stroke of the reciprocating 10

member to force the packed core into the empty container.
